UNITED STATES PATENT OFFICE.

OWEN H. JONES, OF HARTFORD, CONNECTICUT, ASSIGNOR OF ONE-HALF TO
FRANK C. SMITH, OF NEW YORK, N. Y.

CAR-VENTILATOR.

SPECIFICATION forming part of Letters Patent No. 293,967, dated February 19, 1884.

Application filed May 14, 1883. (No model.)

To all whom it may concern:

Be it known that I, OWEN H. JONES, of Hartford, in the county of Hartford and State of Connecticut, have invented new and useful Improvements in Car-Ventilators, of which the following is a specification, reference being had to the accompanying drawings.

Heretofore the construction of car-ventilators adapted to exhaust the air from the car has to been complicated and expensive.

The object of my invention is to construct a car-ventilator which shall be of simple and cheap construction, by which the exhaust is caused to operate by the moving of the car to which the device is attached.

My invention consists in the construction herein set out, whereby desirable advantages are attained.

In the accompanying drawings, in which like letters of reference indicate like parts, Figure 1 is a side view of a section of a car-bottom with my device applied thereto, the air-box being in section. Fig. 2 is a view of the device as seen from the end of the car.

The construction will be readily understood on reference to the drawings.

a represents an air-box, having a means of communication with the interior of the car, and having also a contracted outlet, *b*.

c represents a fan adapted to revolve within the air-box *a*, drawing the air from the opening in interior of the car and forcing it out of

the orifice *b*. The wind-wheels *d* and *e* are arranged upon each side of the air-box, and are preferably secured to the same shaft. The 35 blades of the wind-wheels slant in the same direction, so that the tendency of both is to turn in the same direction when the car is in motion. The burden of the work will of course be performed by the wheel which is in front 40 of the air-box, this depending on the direction in which the car moves. The interior of the air-box and the car are connected either by a direct opening from one to the other or by means of tubes *g*. Suitable registers in the 45 car enable the occupants to control the current.

I am aware of United States Letters Patent Nos. 274,063 and 11,101, and I make no claim to the construction therein shown.

Having therefore described my invention, 50 what I claim, and desire to secure by Letters Patent, is—

As a car-ventilator, the air-box *a*, adapted to be secured to a car, in combination with tubes *g*, adapted to connect the interior of the 55 car with the interior of the air-box, and the shaft *f*, having fan *c* and two wind-wheels, *d* *e*, all constructed and operating substantially as shown.

OWEN H. JONES.
